(57) CLAIM

The ornamental design for a display screen with icon or product with surface ornamentation, as shown and described.

DESCRIPTION

FIG. 1 is a perspective view of a product with surface ornamentation showing the present invention;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a front view of a display screen with icon showing the present invention.

The dash broken lines showing the product in FIGS. 1-7 and the display screen in FIG. 8 are directed to environment and form no part of the claimed design.

1 Claim, 7 Drawing Sheets
